UNITED STATES PATENT OFFICE

BENEDICT COLAVECCHIO, OF PROVIDENCE, RHODE ISLAND

DESIGN FOR A BUCKLE

Application filed November 5, 1930. Serial No. 37,550. Term of patent 3½ years.

To all whom it may concern:

Be it known that I, BENEDICT COLAVECCHIO, a citizen of the United States of America, residing in Providence, county of Providence, State of Rhode Island, have invented a new, original, and ornamental Design for a Buckle, of which the following is a specification, reference being had to the accompanying drawing, forming a part thereof.

Fig. 1 is a top plan view of a buckle, showing my new design; and Fig. 2 is a side elevation of the same.

I claim:

The ornamental design for a buckle, substantially as shown.

BENEDICT COLAVECCHIO.
